LOOM SHUTTLE

Carl D. Brown, Hopedale, Mass., assignor to
Draper Corporation, Hopedale, Mass., a cor-
poration of Maine

Application August 8, 1941, Serial No. 406,017

5 Claims. (Cl. 139—212)

The present invention pertains to loom shuttles and more particularly relates to tension devices of such shuttles for tensioning the running filling thread therein.

Shuttles of the type to which my invention pertains commonly comprise a shuttle body adapted to carry a supply of filling thread, thread delivery means for delivering or paying out the running filling thread when the shuttle is in operation in the loom, and a tension device for maintaining a predetermined tension on the running filling thread. Such tension devices commonly comprise at least one tension member engaging the running filling thread and movable transversely thereof to tension the same, such member being yieldingly urged against the running filling thread by a spring such as a coiled spring or a rubber band.

Prior tension devices of the type mentioned are subject to numerous disadvantages, including the possibility of collapse or breakage of the very delicate spring or the rubber band, the impossibility of providing a single spring suitable for or adjustable to accommodate all kinds and sizes of filling thread, the difficulty of accurately adjusting spring tension to provide the desired tension on the filling thread, and the non-uniform tension provided by such spring or rubber band and resulting from inertia or vibration or other causes.

A principal object of the present invention is to provide a shuttle carrying a supply of filling thread and having thread delivery means and tension devices including a movable tension member as aforesaid, and improved means comprising a magnet for yieldingly urging such tension member into tensioning engagement with the running filling thread, thereby eliminating the aforesaid disadvantages of prior constructions.

The foregoing and other objects of the invention are accomplished in the construction illustrated on the accompanying drawing, of which:

Fig. 1 is a plan view of the thread delivery and of a shuttle comprising the preferred embodiment of my invention;

Fig. 2 is a view of the same in section taken approximately on line 2—2 of Fig. 1;

Fig. 3 is view partly in plan and partly in section approximately on line 3—3 of Fig. 2, but to a larger scale; and

Fig. 4 is a view in cross-section taken approximately as indicated by line 4—4 of Fig. 3.

The particular shuttle shown on the drawing comprises a shuttle body 1 of usual construction

except as modified to accommodate the tension adjusting means hereinafter described. The shuttle body 1 has a cavity 2 for receiving a supply of filling thread 3, which may be carried by a bobbin 4, and held in the shuttle by suitable usual means not shown, all as is usual in shuttles of this type.

The shuttle also has thread delivery means of any suitable type such as a threading block 5 which may be made of any appropriate non-magnetic material, such as brass, and side delivery eye 6. The threading block 5 has front and rear walls 7 and 8, respectively, forming a thread passage 9 extending longitudinally of the shuttle. The running filling thread F extends from the bobbin 4 through the thread passage 9 and thence out the side delivery eye 6.

The particular shuttle shown being for an automatic bobbin changing loom, the threading block 5 may include a horn 10 and guard 11 of usual construction for automatically threading the filling thread F down into its normal running position in the thread passage 9 and eye 6.

Under certain operating conditions, and with certain types of filling thread, particularly rayon and the like, the friction of the fixed surfaces of the thread delivery means is not sufficient to maintain proper tension on the running filling thread. In such cases, a tension device for exerting additional tension on the running filling thread is provided. Various constructions of tension devices have been used for this purpose, such devices including at least one tension member movable into engagement with the running filling thread for tensioning the same. One form of such member is shown at 12 on the drawing.

The particular tension member 12 is a friction member or pad adapted to be yieldingly pressed against the running filling thread F to thereby frictionally tension the latter. Preferably, the pad 12 presses the thread F against a friction surface, which may comprise the front surface of a pad 13, as in the prior "spring clamp" type of tension device.

The particular friction pads 12 and 13 comprise a pair of opposed pads which are positioned in the thread passage 9 on opposite sides thereof, the pad 12 being on the front side of the passage and the pad 13 being on the rear side thereof. Each such pad comprises a vertically elongated body and the pads are loosely mounted in the thread passage on a fixed transverse pin 14 adjacent the bottom thereof. It will be apparent that, except as otherwise controlled, the pads 12 and 13 are free to move transversely of the shut-

tle and thread passage and also toward and away from each other. When the running filling thread F is threaded into the shuttle it is positioned between the pads 12 and 13 and will be frictionally tensioned when such pads are pressed together.

The present invention contemplates using a magnet to yieldingly urge a movable tension member against or into tensioning engagement with the running filling thread. In the particular embodiment shown, a magnet 15 is constructed and arranged to yieldingly urge the pads 12 and 13 together. This magnet 15 may act directly on at least one of the pads, in this instance pad 12, and such pad is accordingly so constructed that it has the property of being attracted by a magnet. This property may be imparted to the pad simply by constructing the pad of a suitable ferrous metal. The other pad, 13, may also be constructed of ferrous metal, but this is not of consequence in the particular embodiment shown.

The magnet 15 may be of a conventional modified horseshoe shape as shown, and is preferably of a type having a very strong magnetic field. The magnet is positioned back of the thread passage 9 and pads 12 and 13, with its poles extending toward the pads in alignment therewith. To this end, the shuttle body 1 may be recessed as shown on Fig. 3 and the back wall 8 of the threading block 5 may be recessed as shown at 16 and 17 on Fig. 4, to support the magnet in the back wall of the threading block.

The pads 12 and 13 being within the magnetic field of the magnet 15, they will be attracted rearwardly toward the magnet. The construction includes stop means for limiting rearward movement of the pad 13 toward the magnet. As shown, such stop means may consist of the top part 18 and the bottom part 19 of the back wall 8, which parts are positioned between the magnet 15 and pad 13 and directly engage the latter. Rearward movement of the pad 13 being thus limited, the pad 12 will be attracted or pressed against the pad 13, or against the running filling thread F when the latter is located between the pads.

It will be apparent that the force exerted by the magnet 15 on the pad 12 will vary with the distance between the magnet and pads. The present invention contemplates providing for adjustment of the tension of the filling thread by adjusting the position of the magnet relative to the tensioning member.

A spring 20 and a threaded member such as screw 21 constitute a simple and effective adjusting means for the purpose above described. This spring 20 is a coiled compression spring supported in a hole in the back wall 8 of the threading block as shown by Figs. 3 and 4. One end of the spring bears against the bottom of said hole and the other end bears against the magnet 15, whereby the spring yieldingly urges the magnet rearwardly. The screw 21 is threaded into an aperture 22 in the shuttle block 1 and bears against the back of the magnet 15. Turning the screw 21 forwardly will move the magnet 15 forwardly against the action of spring 20 and thereby increase the force exerted by the magnet on the pad 12.

It will be apparent that the embodiment shown and above described eliminates all of the aforesaid disadvantages of prior constructions. In addition, the magnetic control is found to be much superior to prior constructions when used

with filling thread having knots, slubs, or of varying diameter. When a knot or thick portion of the thread engages the tensioning member, it moves the member away from the magnet, and

5 thereby reduces the force exerted on the member by the magnet. This allows the knot or the like to pass through the tension device without imposing undue strain on the filling thread. The magnetic force restores the tension member to 10 normal tensioning position immediately following the passage of any such knot or the like.

Having fully disclosed the preferred embodiment of my invention, I claim:

1. A loom shuttle comprising a shuttle body 15 adapted to carry a supply of filling thread, thread delivery means providing a path for the running filling thread, cooperating tension members engaging the running filling in said path, at least one of said members being movable to thereby cause said members to tension said running filling thread, a normally stationary magnet separate from said members and constructed and arranged to yieldingly move said movable member as aforesaid, a stop means for maintaining said members in spaced apart relationship with said magnet, and means to adjust the position of said magnet to control the effect thereof on said movable member.

2. A loom shuttle comprising a shuttle body 30 adapted to carry a supply of filling thread, thread delivery means including a longitudinal thread passage for the running filling thread, tension means in said thread passage comprising a pair of opposed movable friction pads 35 adapted to grip said running filling thread to thereby tension the same, at least one of said pads having the property of being attracted by a magnet, a magnet adjustably positioned to attract the last said pad toward the other said pad for the purpose described, and a stop means for limiting the movement of said pads in the direction of said magnet.

3. A shuttle for automatic bobbin changing looms, said shuttle including a threading block 45 having a longitudinal thread passage for the running filling thread, a pair of opposed friction pads positioned in said thread passage on opposite sides thereof and adapted to grip said filling thread to thereby tension the same, at 50 least one of said pads having the property of being attracted by a magnet, a magnet carried by said threading block and located adjacent said pads in position to attract said magnetic pad against the other of said pads, and a stop 55 engaging said other pad for limiting movement of the latter in the direction of the force exerted by said magnet.

4. A shuttle for automatic bobbin changing looms, said shuttle including a threading block 60 having a longitudinal thread passage for the running filling thread, a pair of opposed friction pads mounted in said thread passage for movement transversely thereof, said pads being adapted to frictionally grip said filling thread to 65 thereby tension the same, said pads being formed of a ferrous metal, a magnet carried by said threading block at one side of said pads in position to attract both of said pads transversely of said thread passage, and a stop located between 70 said magnet and said pads in position to limit movement of the latter toward said magnet, whereby said pads are yieldingly urged together by said magnet.

5. A loom shuttle comprising a shuttle body 75 adapted to carry a supply of filling thread, a

movable friction member constructed and arranged to frictionally engage and thereby tension the running filling thread, said member having the property of being attracted by a magnet, a magnet arranged to attract said member into frictional engagement with said running filling thread, and means for adjusting said magnet toward and away from said member to

thereby vary the force exerted by said magnet on said member, said means comprising a spring yieldingly urging said member in one direction and a threaded device for positively moving said magnet in the other direction against the action of said spring.

CARL D. BROWN.
